UNITED STATES PATENT OFFICE.

FRED J. KEPPLER, OF BUFFALO, NEW YORK.

CONVERTIBLE BUILDING.

Application filed May 22, 1920. Serial No. 383,419.

To all whom it may concern:

Be it known that I, FRED J. KEPPLER, a citizen of the United States, residing at Buffalo, in the county of Erie and State of New York, have invented new and useful Improvements in Convertible Buildings, of which the following is a specification.

This invention relates to a convertible building and more particularly to a building provided with removable partitions and posts which can be variously arranged to suit the required division of the available space between the floor and ceiling of the building.

The object of this invention is the provision of means for mounting the partition and posts between the floor and ceiling which permit of erecting and dismantling the same quickly and easily and without the use of tools or necessitating any trying and fitting.

In the accompanying drawings: Figure 1 is a fragmentary vertical section of a building equipped with my improvements. Figures 2 and 3 are fragmentary vertical sections taken on the correspondingly-numbered lines in Fig. 4. Figures 4, 5 and 6 are horizontal sections taken on the correspondingly numbered lines in Fig. 2. Figure 7 is a vertical section taken on line 7—7, Fig. 2. Figure 8 is a horizontal section taken on line 8—8, Fig. 7. Figures 9 and 10 are fragmentary perspective views of the follower and the partition, respectively.

Similar characters of reference indicate corresponding parts throughout the several views.

11 represents the floor of the building and 12 the ceiling thereof both of which are horizontal and may be incorporated in the building in any suitable or approved manner. Between the ceiling and floor a plurality of posts 13 and partitions 14 are mounted for dividing this space, as desired. The means for securing the posts and partitions in place are constructed as follows:

Between the upper and lower ends of each post and the ceiling and floor are arranged two coupling devices whereby the post and adjacent partitions are connected with each other and the floor and ceiling. As these upper and lower coupling devices are alike in construction and operation, the following description of one applies to all of them:

15 represents the hollow body of the cou-

pling device which is provided with a horizontal base plate 16 adapted to engage either the floor or the ceiling as a support and provided with a central hollow hub 60 and a plurality of hollow sections 17, preferably four, arranged around said hub. Centrally within the hub is arranged a vertical socket or tubular guide 18, the outer end of which is vertically in line with a centering pin or dowel 19 on the adjacent end of the post. The upper coupling body is preferably fixed on the ceiling by means of screws 20 but the lower coupling body is held in place on the floor simply by friction. In order to retain the post in place between the companion upper and lower coupling bodies, pressure is exerted against each end of the post by a cup-shaped presser head 21 which is movable vertically and guided in the socket of the respective coupling body but limited against outward movement by a stop bolt or guide rod 22 arranged centrally in the guide 18 and provided at its lower end with a stop head 23 while its upper end is secured to the respective base plate. 24 is a spring arranged in the tubular guide around the guide rod and bearing at its lower end against the presser plate while its upper end bears against a vertically movable follower 25 sliding within the guide tube. The downward movement of the follower is produced by one or more horizontally movable wedges 26 which are guided on the coupling body and provided at their inner ends with inclined surfaces 27 engaging with correspondingly inclined surfaces 28 on the follower. In the preferred construction, two pairs of such wedges are employed on diametrically opposite sides of the hub of the coupling body, the members of each pair being arranged parallel and on opposite sides of a pair of guide ribs or flanges 29 on the front side of the respective base plate. At their outer ends the wedges of each pair are connected by a pin 30 which passes through short horizontal slots 31 in the wedges and long horizontal slots 32 in the ribs 29. On the central part of this pin is mounted the outer end of a locking link 33 which latter is guided to move vertically at its inner end on the adjacent part of the hub of the coupling body, this being preferably accomplished by means of a transverse pin 34 arranged on the inner end of the link 33 and engaging

with vertical slots 35 formed in a pair of upright guide ribs 36 in the hub between which the inner end of the link moves. The raising and lowering of the latter may be effected by various means, for instance, by a pair of vertical shifting rods or handles 37 connected at their ends with opposite ends of the pin 34 and provided at their front ends with eyes 38 which are adapted, in the operative position of this link, to be secured to eyes 39 on the adjacent part of the post by means of pins 40.

At right angles to the locking links 33 similar locking links 41 are arranged on diametrically opposite sides of the hub of the coupling body and each guided at its outer end by means of a pin 42 thereon engaging with horizontal slots 43 in the ribs 61 of the adjacent body section while its inner end is guided on a pin 44 thereon engaging with vertical slots 45 in ribs 46 on the hub. The pin 44 is provided at its ends with vertical shifting rods 47 which are provided with eyes 38 adapted to be locked to eyes 39 on the post on opposite sides of the partition by means of pins 40.

Each of the partitions has each of its four corners cut out to form a recess 51 which is adapted to receive one of the sections of one of the coupling bodies while the horizontal upper and lower edges of the partition engage the ceiling and the floor and the vertical edges of the same engage the opposing sides of a pair of companion posts. The horizontal surface of each of these recesses is provided with a socket 52 which is preferably formed in a cap 53 of metal secured to the partition by screws 42 to reduce the wear upon the same.

In the operative position of each of the links 33 and 41 the same is arranged in inclined position and extends from the outer end of the respective body section to the lower part of the hub thereof and if a partition engages with the respective facet of the post, the locking links associated with the adjacent posts engage with the locking sockets 52 of the partition and hold the same in place. By securing the shifting rods of these links to the posts on opposite sides of each partition by means of the pins 40, a person occupying a room on one side of the partition is prevented from removing the partition and gaining access to the room on the other side, thus insuring safety and privacy.

In the operation of erecting the posts and partitions to divide the space into rooms, each post is first placed in an upright position between one of the fixed coupling bodies on the ceiling and another such body arranged in line therewith on the floor, the lower dowel of the post being engaged with the presser head in the socket of the lower coupling body, while the upper dowel of the

post is engaged with the presser head of the upper coupling body. If four partitions are to be associated with each post two of them are first placed in line with those arms of the upper and lower companion coupling bodies which contain the pairs of wedges, after which the locking links 33 are shifted by means of the rods 37 from their horizontal inoperative position, shown by full lines at the left of Fig. 2, to their inclined position, shown at the right of the same figure, in which last mentioned figure each of these links interlocks with a socket 52 of the adjacent partition and holds the same in an upright position. The shifting of the links from the horizontal to the inclined position also causes the wedges associated therewith to be moved inwardly whereby the followers are moved toward the ends of the respective post, whereby the springs 24 are flexed or strained and pressure is exerted and the presser heads 21 are held firmly in engagement with the ends of the post, so that the latter will resist displacement. The links 33 are then locked in their operative position by means of the pins 40.

By providing the wedges with comparatively short slots 31 and the ribs 29 with long slots 32, the links 33 are capable of moving horizontally to some extent independently of the wedges and thus permit of moving the latter a comparatively short distance sufficient to operate the respective follower while permitting the inner ends of the links to move vertically a sufficient extent to properly interlock with the sockets at the corners of the partition. The other two partitions are now similarly engaged with the other two facets of the post and the adjacent sections of the upper and lower coupling bodies and then the links 41 are shifted from a horizontal position into an inclined position for engaging the same with the sockets 52 of the partition, so that the same is retained in place after which these links are likewise held in their operative position by means of the pins 40.

If less than four partitions are to be employed in connection with a post, only those locking links are moved from their horizontal position to an inclined position which are in line with a partition so as to engage with the socket of the latter and hold the same upright, but when only one partition is employed the same must be placed in line with links which are associated with wedges so that the post will be clamped to the ceiling and floor at the same time that the respective partition is locked in an upright position.

In order to conceal the working parts within each hollow body and prevent the same from being seen from within the rooms, the front side of each body is provided with a cover 54 which has slots 55 through which

the links are free to move, this cover being attached to the body by screws 56 or other suitable means.

I claim as my invention:

- 5 1. A convertible building having a support, a coupling body mounted on said support, a post arranged in line with said body, and clamping means interposed between said body and post comprising a presser head adapted to engage the end of said post, a spring bearing against said head, and means for flexing said spring.

- 10 2. A convertible building having a support, a coupling body mounted on said support, a post arranged in line with said body, and clamping means interposed between said body and post comprising a presser head adapted to engage the end of said post, a spring bearing against said head, and means for flexing said spring, comprising a follower bearing against said spring, a wedge adapted to shift said follower and means for shifting the wedge to engage and shift the follower to flex the spring.

- 15 3. A convertible building having a support, a coupling body mounted on said support, a post arranged in line with said body, and clamping means interposed between said body and post comprising a presser head adapted to engage the end of said post, a spring bearing against said head, means for flexing said spring, comprising a follower bearing against said spring, a wedge adapted to shift said follower, a link connected 20 with said wedge and with said body, and means for operating said link and retaining the same in place.

- 25 4. A convertible building having a support, a coupling body mounted on said support, a post arranged in line with said body, and clamping means interposed between said body and post comprising a presser head adapted to engage the end of said post, a spring bearing against said head, and means for flexing said spring comprising a follower bearing against said spring, a wedge adapted to shift said follower, a link connected 30 with said wedge and with said body, and means for operating said link and retaining the same in its operative position in which said wedge presses the spring against said head.

- 35 5. A convertible building having a support, a coupling body mounted on said support, a post arranged in line with said body, and clamping means interposed between said body and post comprising a presser head adapted to engage the end of said post, a spring bearing against said head, and means for flexing said spring comprising a follower bearing against said spring, a wedge adapted to shift said follower, a link connected 40 with said wedge and with said body, and means for retaining said link in its operative position comprising a shifting rod con-

nected with said link and provided with an eye, and a pin arranged on said post and adapted to receive said eye.

6. A convertible building having a support, a coupling body mounted on said support, a post arranged in line with said body, and clamping means interposed between said body and post comprising a presser head adapted to engage the end of said post, a follower, a spring interposed between said presser head and follower, a guide rod which is slidably connected with said follower and upon which said presser head slides, a wedge guided on said body and engaging said follower, and a link connected with said wedge and with said body and adapted when moved into an inclined position to shift said wedge into engagement with said follower.

7. A convertible building having a support, a coupling body mounted on said support, a post arranged in line with said body, and clamping means interposed between said body and post comprising a presser head adapted to engage the end of said post, a follower, a spring interposed between said presser head and follower, a guide rod which is slidably connected with said follower and upon which said presser head slides, a horizontal wedge guided to move horizontally on said body and engaging with said follower, and a link connected at one end with said wedge and slidably connected at its opposite end with said body to move vertically on the latter.

8. A convertible building having a support, a coupling body mounted on said support, a post arranged in line with said body, a partition arranged adjacent to said support, post and body and provided in the adjacent corner with a socket, and independent means arranged on said body and engaging with said socket.

9. A convertible building having a support, a coupling body mounted on said support, a post arranged in line with said body, a partition arranged adjacent to said support, post and body and provided in the adjacent corner with a socket, and independent clamping means arranged between said body and post and having a member engaging with said socket.

10. A convertible building having a support, a coupling body mounted on said support, a post arranged in line with said body, and clamping means interposed between said body and post comprising a presser head adapted to engage the end of said post, a follower, a spring interposed between said presser head and follower, a guide rod which is slidably connected with said follower and upon which said presser head slides, a horizontal wedge guided on said body and engaging said follower, a link connected with said wedge and guided vertically on said body, and a partition provided

in its corner with a socket which receives said link.

11. A convertible building comprising a support, a post and a partition arranged adjacent to said support and post and provided with a socket, and independent means for securing said post to said support comprising a movable locking member engaging with said socket.

12. A convertible building comprising a support, a post and a partition arranged adjacent to said support and post and provided with a socket, and means for securing said post to said support comprising a locking link slidable horizontally and vertically on said support and adapted to move into and out of engagement with said socket.

FRED J. KEPPLER.
